WINDOW OPERATING DEVICE

Filed Oct. 19, 1928

Inventor

John W. Frank.

By Adam E. Fisher.

Attorney

UNITED STATES PATENT OFFICE

JOHN W. FRANK, OF MUSCATINE, IOWA

WINDOW-OPERATING DEVICE

Application filed October 19, 1928. Serial No. 313,470.

This invention relates to a window operating device and more particularly to a device for raising and lowering a plurality of windows simultaneously which device is operable from a point remote from the said windows.

The main objects of the invention are the provision of such a device in a simple and durable form which may be readily attached to the window frames and sash now in use and which is operated by an electric motor controlled by a switch placed in any convenient position.

The foregoing and other objects of the invention together with means whereby the same may be carried into effect will best be understood from the following description of a preferred embodiment of the invention taken in connection with the accompanying drawing in which:

Figure 1 is an elevation of a portion of a building wall showing the windows therein provided with my invention.

Figure 2 is an enlarged elevation of a portion of a window frame and associated sash showing parts of my invention applied thereto; and Figure 3 is a section along the line 3—3 in Figure 2.

Referring now more particularly to the drawing the reference numeral 1 denotes a pair of conventional windows in the wall 2 each of which comprises the frame 3 and upper and lower sashes 4 and 5. A line shaft 6 is journaled through hangers 7 secured to the wall, the said shaft extending across the windows at a point adjacent the upper ends thereof as shown. This line shaft 6 is rotated by means of an electric motor 8 secured to the wall and this motor is controlled by a conventional reversing switch 9 which may be placed in any convenient position and which allows the direction of rotation of the motor to be reversed at will for a purpose to be set forth.

45 Bearings 10 are secured to each side of the

frame 3 in alignment with the line shaft 6 and stub shafts 11 are journaled therein, the said shaft 11 extending into the frame 3 through apertures 12 therein. Beveled gears 13 are secured upon the outer ends of the stub shafts 11 and beveled pinions 14 are secured upon the line shaft 6 and placed in mesh with these gears, the said pinions 14 being arranged oppositely as shown so that the beveled gears 13 in each window will be turned in opposite directions. Peripherally grooved pulleys 15 are secured upon the inner ends of the stub shafts 11 in any suitable manner such as by the nuts 16 and cotter keys 17. The sash cords 18 are secured at one end to the lower sash 5 as shown at 19 and are trained over the pulleys 15 and provided at their opposite ends with sash weights 20.

In the use and operation of the device the switch is operated in the proper manner to cause the motor to rotate the line shaft, which through the beveled gears and pinions will turn the grooved pulleys and raise the windows. The windows may be lowered by reversing the direction of the rotation of the motor as will be understood.

In the construction and use of this invention, the pulleys 15, for carrying the sash cords 18, are made smooth upon their peripheries and thus these cords take up any shock of the sash when same is raised or lowered by simply gliding over the pulleys when the sash reaches the end of its movement in either direction. The operator simply closes the current through the main motor for two or three seconds, and the windows are raised or lowered, any excess movement of the pulleys being immaterial. One motor will suffice for the entire battery of windows through the employment of the connecting shaft 6.

While I have herein set forth a certain preferred embodiment of my invention, it is understood that I may vary from the same in minor details, not departing from the

spirit of the invention and within the scope
of the appended claim.

I claim:

5 In a device of the character described, in
combination with a window frame and slide-
able sash therein, peripherally smooth pulleys
rotatably mounted in the window frame above
the sash, means for rotating the said pulleys,
10 sash cords secured at one end to the sash and
trained over the pulleys, and weights upon
the free ends of the sash cords.

In testimony whereof I affix my signature.

JOHN W. FRANK.
